UNITED STATES PATENT OFFICE.

FRANK D. BAKER, OF DENVER, COLORADO.

ORE-COOLER.

943,294.

Specification of Letters Patent. Patented Dec. 14, 1909.

Application filed November 7, 1908. Serial No. 461,481.

To all whom it may concern:

Be it known that I, FRANK D. BAKER, a citizen of the United States, residing at the city and county of Denver and State of Colorado, have invented certain new and useful Improvements in Ore-Coolers; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 My invention relates to improvements in ore coolers, more especially adapted for use in cooling the ore after it has been roasted, and prior to its treatment for the purpose of saving its metallic values.

20 The object of my present invention is to provide means of simple and economical construction which shall effectually and quickly perform the ore-cooling function, and to this end I provide a rotary cooler 25 having cone-shaped extremities, and a cylindrical body portion. Its axis occupies a horizontal position. This cooler is mounted to rotate in water which is contained in a suitable receptacle, which water is continually changing, due to a constant supply 30 from a suitable source, thus keeping its temperature at a reasonably low point at all times. The depth of the water in which the cooler rotates is as great as practicable.

35 The water by virtue of its buoyancy forms a support for the cooler and makes it practicable to use a longer cooling apparatus than would be otherwise possible. In order to properly cool the ore, an apparatus of considerable length is required and it is important 40 that bearings intermediate the extremities of the rotary cooler be dispensed with. Hence, the water not only serves to perform the ore-cooling function, but it also forms the necessary and the most desirable support 45 for the cooler intermediate the extremities of the latter.

The cone-shaped extremities of the cooler are provided with cylindrical extensions 50 forming hollow trunnions which engage suitable bearings. The cooler is equipped with an operating gear which may be connected with any suitable power for purposes of rotation. The cylindrical body portion 55 of the cooler is equipped with flights which simultaneously stir and advance the ore to-

ward the discharge extremity of the apparatus. The cone-shaped discharge end of the cooler is equipped with a spirally arranged blade which advances the ore toward the open extremity of the cooler where it is finally discharged in a properly cooled condition. Water is also delivered to the top of the cooler by a pipe mounted above the same and continually discharging water 60 thereon. This water runs down over the cooler and mingles with the water below, which is continually over-flowing at one end of the same.

Having briefly outlined my improved construction, I will proceed to describe the same in detail, reference being made to the accompanying drawing in which is illustrated an embodiment thereof.

In this drawing, Figure 1 is a side elevation of my improved cooling apparatus, the receptacle for the cooling water being partly broken away. Fig. 2 is a top plan view of the same. Fig. 3 is a vertical longitudinal section taken through the cooler on the line 3—3 Fig. 4. In this view the cylindrical portion of the cooler is shown broken to indicate that its length should be very much greater than shown in the drawing, in order to harmonize with its diameter as there indicated. Fig. 4 is a cross section of the cooler taken on the line 4—4 Fig. 3. Fig. 5 is a fragmentary sectional view of one extremity of the cooler. Figs. 3, 4 and 5 are shown on a larger scale than in the other views.

The same reference characters indicate the same parts in all the views.

Let the numeral 5 designate a tank containing water 6, in which the ore cooler 7 is mounted to rotate on a horizontal axis. This cooler is composed of a cylindrical body part 8 and cone-shaped extremities 9 and 10. These extremities are frusto-conical their smaller ends being equipped with hollow trunnions 12 and 13 mounted in bearings 14 and 15 provided with anti-frictional rollers 16. The ore to be cooled is discharged into the cone-shaped extremity 9 by a conduit 17 and passes downwardly to the cylindrical body 8 of the cone which is equipped with flights 18 suitably arranged to advance the ore toward the discharge extremity and simultaneously stir the same to facilitate the cooling operation. The cone-shaped extremity 10 of the cooler is provided with a spirally arranged blade causing the ore to travel

gradually upwardly to the discharge end 19 of the cooler, from the lowest part of the cylindrical body of the cooler.

The main portion of the cooler may be 5 made of any desired length which may be necessary in order to sufficiently lower the temperature of the ore to enable it to be subjected to the operations necessary for the saving of its metallic values.

10 The necessary rotary motion is imparted to the cooler by any suitable power. As shown in the drawing, the frame-work 20 at the discharge extremity of the cooler, is equipped with a shaft 21 upon which are 15 mounted fast and loose pulleys 22 which may be connected with a rotating shaft or any suitable motor. It is evident that the shaft 21 may be located at any suitable point.

Mounted upon the pulley shaft 21 is a pinion 23 meshing with a relatively large gear 24 fast upon a shaft 25, which is also equipped with a smaller gear 26 meshing with a relatively large gear 27, which as shown in the drawing is fast upon the discharge extremity of the cooler. This gear may be applied to any other suitable part of the cooler. By virtue of this construction, a relatively slow rotary movement is imparted to the cooler, since the relative size of 30 the denominated gears has a speed reducing effect.

The tank 5 is continually supplied with cooling water from a pipe 35 having a controlling valve 36. The water overflows from 35 one end of the tank through an opening 30, passing first into a chamber 31 formed in the wall of the tank, and escaping therefrom through an opening 32. The end of the tank opposite the inlet pipe 35 is provided 40 with a drain pipe 28 having a valve 29.

To facilitate the cooling of the ore, a pipe 33 is mounted above the cooler and perforated to discharge jets or sprays 34 of water upon the top thereof. This water flows 45 down upon the opposite sides of the cooler and serves to lower the temperature of the latter, thus facilitating the cooling of the ore traveling through the apparatus.

From the foregoing description the use 50 and operation of my improved ore cooler will be readily understood. Assuming that the tank 5 is filled with cooling water, the cooler is set in motion, its speed being comparatively slow as indicated by the train of 55 speed-reducing gears connected with the discharge extremity thereof, and heretofore described.

The cooling water is continually changing 60 within the tank 5 by virtue of the supply provided by the pipe 35 at one extremity, and the over-flow of the cooling water at the other extremity of the tank. The ore is fed into the cone-shaped end 9 of the cooler and passes downwardly to the cylindrical body 65 portion thereof, which, by virtue of its

flights, is continually raising the ore as the cooler rotates, and dropping it, thus simultaneously stirring and advancing the ore. In this manner it is gradually advanced from the frusto-conical inlet to the correspondingly shaped outlet end of the cooler. As soon as it reaches the latter it is acted upon by the interiorly located spiral blade which gradually carries it to the discharge end of the cooler.

As heretofore stated, the buoyancy of the water has a tendency to float the cooler, and forms a support therefor, whose magnitude is equal to the weight of the body of liquid displaced. By virtue of this liquid support 80 intermediate the end trunnions of the cooler, the latter may be given considerable length without danger of sagging or breaking. This is a very important feature in constructions of this class. I also wish to emphasize 85 the fact that my improved cooler is mounted to rotate on a horizontal axis, as distinguished from coolers which occupy an inclined position. In my cooler provision is made for advancing the ore from the inlet 90 to the discharge extremity thereof, whereby there is no necessity for mounting the cooler in an inclined position. I further wish to call attention to the fact that the tank 5 is supplied with water at the extremity remote 95 from the inlet extremity of the cooler, whereby water is flowing through the cooling tank in a direction opposite the travel of the ore through the cooler, whereby I obtain a counter-stream advantage.

Having thus described my invention, what I claim is:

1. In ore cooling apparatus, the combination with a water containing receptacle, of an ore cooler mounted to rotate in said receptacle and having end supports only, the cooler being partly immersed in the water intermediate its extremities, whereby the buoyancy of the water serves as a support, means for feeding the ore to the cooler, the latter being equipped with means for continually advancing the ore from the inlet to the outlet extremity thereof, substantially as described.

2. In ore cooling apparatus the combination with a water containing receptacle, a cooler mounted to rotate in said receptacle in direct contact with the water in which it is partly immersed, the cooler having end supports only being open at its opposite extremities for the reception and discharge of the ore, the cooler being equipped with means for simultaneously stirring and advancing the ore during the cooling operation, substantially as described.

3. In ore cooling apparatus the combination with a water containing receptacle, of a cooler mounted to rotate therein, and comprising a cylindrical body part, equipped with flights for stirring and advancing the

ore, the cooler having frusto-conical extremities for receiving and discharging the ore, the discharge extremity of the cooler having a spirally arranged blade for carrying the ore from the body of the cooler to the discharge end of the latter, substantially as described.

4. In ore cooling apparatus, the combination of a receptacle for the cooling water, a cooler partly immersed in the water intermediate its extremities, having end supports only, the cooler being mounted to rotate in the receptacle and equipped with means for stirring and advancing the ore, provision being made for continually supplying the receptacle with water, the said receptacle being constructed to permit the water to overflow therefrom, substantially as described.

5. In apparatus of the class described, the combination of a water containing receptacle, means for continually changing the water in said receptacle, a cooler mounted to rotate in the receptacle in direct contact with the water and having end bearings only, the cooler being equipped with means for stirring and advancing the ore, during the cooling operation, means for discharging water upon the top of the cooler, and means for imparting rotary movement to the latter, substantially as described.

6. The combination with a water containing receptacle, means for continually changing the water in said receptacle, a cooler mounted in the receptacle and having a cylindrical body portion and frusto-conical extremities, the said extremities having hollow bearings through which the ore is introduced and discharged, the body of the cooler being equipped with flights for stirring and advancing the ore the cooler being provided with bearings at its ends only, and means connected with the cooler for imparting a relatively slow rotary movement thereto, substantially as described.

7. In apparatus of the class described, the combination of a water containing receptacle and an ore cooler mounted to rotate in said receptacle, and provided with end supports, the water intermediate the extremities of the cooler forming a support for the latter, substantially as described.

8. In apparatus of the class described, the combination of a water-containing tank and an ore cooler mounted to rotate therein and having end bearings only, the buoyancy of the water intermediate said bearings constituting the necessary support to permit the use of a relatively long cooler, substantially as described.

9. In apparatus of the class described, the combination of a water containing tank and an ore cooler mounted to rotate therein on a horizontal axis, the cooler having end supports only and being partially submerged within the water intermediate its extremities whereby the buoyancy of the latter has a tendency to float the cooler, substantially as described.

10. In apparatus of the class described, the combination of a water containing tank, an ore cooler mounted to rotate therein and having end bearings only, the cooler being partially submerged between its extremities, provision being made to allow the water to overflow at one end of the tank, and means for supplying the tank with water at the extremity of the latter opposite the overflow end thereof, the cooler being constructed to cause the ore to travel therethrough, opposite the flow of the water in the tank, for the purpose set forth.

In testimony whereof I affix my signature in presence of two witnesses.

FRANK D. BAKER.
